The ornamental design for a data card, as shown and described.

DESCRIPTION

FIG. 1 illustrates a perspective view of a data card, showing my new design;

FIG. 2 illustrates a front plan view thereof;

FIG. 3 illustrates a rear plan view thereof;

FIG. 4 illustrates a bottom elevational view thereof;

FIG. 5 illustrates a top elevational view thereof;

FIG. 6 illustrates a left side elevational view thereof;

FIG. 7 illustrates a right side elevational view thereof; and,

FIG. 8 illustrates an exploded view thereof.

The broken lines in the figures have been shown for illustration purposes only and form no part of the claimed invention.
